AMUSEMENT DEVICE

Harry B. Stoner, Aurora, Ill., assignor to Stoner
Mfg. Corp., Aurora, Ill., a corporation of Illinois

Application November 16, 1933, Serial No. 698,246

10 Claims. (Cl. 273—121)

This invention relates to an amusement device of the type in which a series of balls are caused to individually travel over a playing surface and eventually find their way into some recess upon the surface, the result of the game being determined in each instance by the sum of the indicia corresponding with the recesses occupied by balls.

In the past, many and various amusement devices or games of this character have been developed, but in each instance of which I am aware, these formerly known devices did not meet the full desires of a player in that each of the balls must of necessity travel substantially the same path as the previous ball did, and consequently the results of the game were dependent to a major extent upon luck or accident rather than upon the skill of a player. In addition, while some of these various devices had figurative divisions in the playing field, a player could not positively select a particular division as that which the ball would initially enter.

With the foregoing in mind, it is an object of this invention to provide an amusement device in the nature of a game board whereupon a ball may be impelled over a playing surface divided into a plurality of zones, and the player can, by exercising reasonable skill, determine which zone the ball shall initially enter.

It is also an object of this invention to provide an amusement device of the character described, wherein a playing surface is substantially divided into a plurality of playing zones by suitable guide means upstanding from the playing surface.

Another object of this invention is to provide an amusement device wherein a ball is impelled over a playing surface, having a plurality of playing zones with means provided for directing the ball initially into a predetermined one of said zones.

A further object of this invention is the provision of a game board in which a ball is caused to travel over a playing surface divided into a plurality of zones, the speed of the ball determining which zone it shall initially enter.

It is also an object of this invention to provide a game board of the character described equipped with guiding means providing a plurality of paths for a ball, and the amount of impetus initially given the ball determining which of said paths will be followed by the ball.

One of the major objects of this invention is to provide an amusement device wherein a ball is caused to travel over a playing surface, and with which device a player may readily elect not only the direction of travel of the ball but also

a particular region of the playing surface in which the ball will begin its scoring activities.

While some of the more salient features, characteristics and advantages of a device embodying this invention have been above pointed out, others will become apparent from the following disclosures.

The invention includes these and other features of construction and combinations of parts hereinafter described and shown in a preferred form on the drawing, as more particularly indicated by the claims.

On the drawing:

Figure 1 is a plan view of an amusement device embodying principles of the present invention, illustrating the activity of a ball on the device.

Figure 2 is an enlarged fragmentary sectional view taken substantially as indicated by the line II—II of Fig. 1.

Figure 3 is also an enlarged fragmentary sectional view taken substantially as indicated by the line III—III of Fig. 1.

Figure 4 is an enlarged fragmentary sectional view taken substantially as indicated by the line IV—IV of Fig. 1.

As shown on the drawing:

In the illustrated embodiment of the present invention, there is shown a game board 5 having a sunken ball race 6 merging into a boundary 7 defining a playing surface or field 8. The ball race 6 and playing surface 8 are preferably upon the same level below that of the outer part of the board 5 so that the boundary 7 is raised or upstanding from the playing surface and maintains a ball upon this surface until the same is removed as explained hereinafter.

The playing field 8 is substantially divided into a plurality of playing zones, in this instance three—A, B and C, by suitable guiding means upstanding from the playing surface. These guiding means are preferably of the same construction and, as seen in the drawing, comprise rails 9, 10 and 11 curved in the proper manner to form the zones A, B and C and each supported from the playing surface by suitable posts 12 at spaced intervals or in any other desirable manner. The rails 9, 10 and 11 are so disposed that, while they substantially divide the board into zones, nevertheless a ball passage is provided between adjacent zones, namely passage 13 between the zones A and B, and passage 14 between zones B and C.

The playing surface 8 is preferably the top of a nonwarping board 15, and is provided in each

of the zones A, B and C with a plurality of apertures 16, each of a size to accommodate one or more balls as may be desired. Disposed beneath the board 15 is a second board 17 which is slideable relatively to the board 15 and in conjunction with the various apertures 16 forms recesses into which balls will lodge. The board 17 may be provided with apertures normally spaced away from the apertures 16, so that after a certain 10 number of balls has been used, the board 17 may be moved until all of the apertures coincide, thereby dropping the balls into a suitable receptacle in a well-known manner. If desired, of course, the board 17 may be stationary and the 15 balls lifted out of the respective recesses by hand.

Any suitable indicia may be applied to the playing surface adjacent the apertures 16, and the sum of these indicia adjacent apertures occupied by a ball denotes the score of a particular 20 player.

Upstanding pins 18, preferably of semi-resilient nature, are disposed at eccentric intervals adjacent the apertures 16. These pins are substantially the same height as the rails 9, 10 and 11, 25 and, by causing the ball to change direction, render the game more tantalizing and interesting.

One of the major features of the present invention is a cam-like switch or guiding means 19 disposed adjacent the passage 13 between the zones A and B, and providing a dual path for a ball. This guiding means 19 is preferably of one piece, and may be wood or other equivalent material or a metal casting. It not only tapers laterally but also vertically, both tapers converging into a point which merges evenly with the boundary 7 where this boundary terminates at the point 20 adjacent zone A. This member 19 is substantially L-shaped in cross-section and the vertical and lateral tapers occur only in the horizontal leg of the L. The vertical taper provides a straight edge 21 (Figures 2 and 3) to serve as a means for guiding a ball into zone A, and this edge is curved to form substantially a continuation of the curvature of the boundary 7 around the zone A. As seen more clearly in Figure 3, the lower portion of the member 19 is formed to gradually provide a groove 22 to guide a ball against the inside of rail 10 and consequently 40 into zone B. A raised portion 23 separates the groove 22 from the inner guiding edge 21. As mentioned above, at the point 20, the lateral and vertical tapers of the members 19 disappear into a single point, the thickness of the member 19 45 at this point being substantially the same as the boundary 7.

Near the top of the board, on the right end thereof as seen in Figure 1, another cam-like switch or guiding member 24 is provided. This 60 member also defines a dual path for a ball. One path is along the inside edge 25 of the member, and the other path is adjacent the boundary 7 directly over the thinnest portion of the member. As seen more clearly in Figure 4, the inner 65 curved end of the member 24 is substantially thick and will not permit the passage of a ball thereover. However, the member tapers gradually toward the boundary 7 until immediately adjacent this boundary, the member is extremely thin. Also, as seen more clearly in Figure 4, the portion of the member next to the boundary is not flat but convex as at 26 so that a ball traveling 70 over the member will retain its position against the boundary 7. The member 24 in effect merges into the boundary 7 at the point 27

so that there is no abrupt change of direction of the ball while guided by either this member or the boundary. The inner curved end of the member 24 preferably hooks around an end of the rail 11 in spaced relationship thereto to thus guide a ball following the edge 25 into the zone C.

In operating the present invention, the device is mounted with one end higher than the other so that the board slopes toward the player and a ball tends to roll by gravity toward an enlarged 10 opening 28 adjacent the bottom of the playing field, the opening 28 usually counting nothing in the score. A ball 29 is given an impulse in the lower end of the race 6, either by hand or any well-known mechanical means. The ball will 15 follow the boundary 7, and will be held against this boundary by centrifugal force at the upper curved portion of the boundary (to the right as seen in Figure 1). When the ball reaches the point 27, if traveling at a relatively low speed, 20 it will follow the inside edge 25 of the guide or switch member 24 and thus enter zone C. The ball may or may not bound against pins 18, and may or may not come to rest in one of the apertures 16 in this zone. If the ball does not come 25 to rest in this zone, in most instances it will strike the outer edge of the rail 10, pass through the passage 14, and follow the inner edge of the rail 11 through the passage 13 and into zone A. If the ball does not come to rest in one of the apertures 16 in zone A, it must by gravity eventually 30 come to rest in the no-score aperture 28.

If, however, the ball 29, as indicated by the dotted lines in Figure 1, has sufficient speed when it reaches the point 27 it will hug the boundary 35 7 and ride over the thin portion of the member 24. The ball will then follow the boundary 7 until it reaches the point 20 adjacent zone A. Upon reaching the point 20, the speed of the ball again determines its direction with the aid 40 of the switch or guide member 19. If the speed of the ball is not sufficient to cause the ball to firmly hug the wall at this point, the ball follows the inner edge 21 of the guide member 19 as indicated by the full line and continues around 45 the inner edge of the rail 12 until it strikes any suitable form of resilient abutment 30, whereupon it rebounds and finds its own course among the pins 18 and apertures 16 in zone A.

If, however, the ball has sufficient speed to 50 hug the wall of the member 19 when it reaches the point 20, it will follow through the groove 22 and be discharged against the inside edge of the rail 10 whereupon it will do either of two things: namely, follow the inner edge of the rail 55 10 clear around until it strikes rail 11 and is thus caused to again enter zone A, or, due to its lack of speed, filter its way among the pins 18 and apertures 16 of zone B and if it does not come to rest there, enters zone A through the passage 13. 60

From the foregoing, it will be seen that a player, with the exercise of reasonable skill, can cause a ball to initially enter and begin its scoring activities in a predetermined zone. With the application of a light impulse, the player may have the 65 ball begin its scoring activities in zone C, but a little stronger impulse, in zone A, and with a still stronger impulse, in zone B. If the impulse is too strong, the ball will not filter its way among the apertures 16 in zone B but will hug the rail 70 10 and subsequently start its scoring activities in zone A.

It is apparent, therefore, that I have provided an amusement device wherein a ball is caused to travel over a playing surface and whereby a 75

player, with the exercise of reasonable skill, may select a particular part of the playing surface for the ball to begin its scoring activities. Consequently, a player can select apertures 16 bearing the higher indicia and so direct successive balls into regions that will best enhance a good score. It is at once obvious that a good score is not contingent upon luck or accident but depends, to a very material degree, upon the skill of the respective player. Furthermore, the entire device is simple in construction, the parts very durable, and the device may be economically manufactured.

I am aware that many changes may be made and numerous details of construction may be varied through a wide range without departing from the principles of this invention, and I, therefore, do not purpose limiting the patent granted hereon otherwise than is necessitated by the prior art.

I claim as my invention:

1. In an amusement device of the character described, a playing surface, a ball race leading to said playing surface, a raised boundary continuing from said ball race and defining said playing surface, means dividing said playing surface into a plurality of playing zones, and guiding means adjacent said boundary and tapering towards said boundary, whereby the speed of a ball following said boundary determines if the ball follows said guiding means or passes therover and thus which zone the ball initially enters.

2. In an amusement device of the character described, a playing surface, a ball race leading to said surface, means dividing said surface into a plurality of playing zones, and a plurality of cam-like switch means in the path of a ball, each of said switch means arranged to alter the direction of travel of a ball or permit a ball to pass by depending upon the speed of the ball.

3. In an amusement device of the character described, a playing surface, a ball race leading to said surface, means dividing said surface into a plurality of playing zones, fixed means shaped to provide a plurality of paths for a ball, said last-mentioned means being located in such relation to said zones that the speed of a ball determines which path is followed and consequently which playing zone a ball initially enters.

4. In an amusement device of the character described, a plurality of playing zones, a boundary around said zones, a ball race merging with said boundary, and a fixed cam-like guiding member adjacent said boundary shaped to direct the ball into any one of a plurality of said zones depending upon the speed of the ball.

5. In an amusement device of the character described, a plurality of playing zones, a ball race leading towards said zones, and a fixed guide member in the path of a ball from said race, said guide member being shaped to define a plurality 5 of paths for the ball to follow, each path leading to a different zone, the speed of the ball determining which path is followed.

6. In an amusement device of the character described, a playing surface, a raised boundary 10 around said playing surface, a ball race disposed so that a ball from said race will tend to follow said boundary, and a fixed guiding member adjacent said boundary in the path of a ball following said boundary shaped to provide a plu- 15 rality of paths for the ball in such relationship that the speed of the ball determines the path followed.

7. In an amusement device of the character described, a playing surface, a raised boundary 20 therearound, a ball race disposed so that a ball therefrom will tend to follow said boundary, and a fixed guide member adjacent said boundary in the path of said ball capable of directing said ball to any of a plurality of regions of said play- 25 ing surface.

8. In an amusement device of the character described, a playing surface, a ball race leading to said surface, an upstanding boundary defining said playing surface, curved guide means up- 30 standing from said surface substantially dividing said surface into a plurality of playing zones, said means being so disposed as to provide a ball passage from one zone to another, and other guide means disposed in the original path of a 35 ball and capable of directing the ball initially into any of said zones.

9. In an amusement device, a playing surface, a ball race leading to said playing surface, and a switch member disposed in the path of a ball 40 from said race and shaped to alter the direction of travel of the ball or permit the ball to pass over the switch member depending upon the speed of the ball.

10. In an amusement device of the character described, a playing surface, a ball race leading to said playing surface, and a switch member disposed in the path of a ball from said race, said switch member being positioned so as to be struck 45 by balls from said race at substantially the same point regardless of the speed of the balls and shaped to change the direction of travel of a ball or permit the ball to pass thereby depending upon the speed of the ball.

HARRY B. STONER.
